Primary Examiner — Eric Goodman*Assistant Examiner* — Clese Moore, Jr.(74) *Attorney, Agent, or Firm* — Mitchell A. Rossman; Tera Nova Patent Law, PLLC.(57) **CLAIM**

The ornamental design for a measuring cup, as shown and described.

DESCRIPTION

FIG. 1 is a perspective view of the design of the present invention.

FIG. 2 is a left side view of the design of the present invention.

FIG. 3 is a right side view of the design of the present invention.

FIG. 4 is a rear view of the design of the present invention.

FIG. 5 is a front view of the design of the present invention.

FIG. 6 is a top view of the design of the present invention; and,

FIG. 7 is a bottom view of the design of the present invention.
